UNITED STATES PATENT OFFICE

111,177

DESIGN FOR A VANITY CASE OR SIMILAR ARTICLE

George Gamble, Cambridge, Mass.

Application April 23, 1938, Serial No. 76,724

Term of patent 3½ years

To all whom it may concern:

Be it known that I, George Gamble, a citizen of the United States, residing at Cambridge, county of Middlesex, Commonwealth of Massachusetts, have invented a new, original, and ornamental Design for a Vanity Case or Similar Article, of which the following is a specification, reference being had to the accompanying drawing, forming part thereof.

Fig. 1 is a top perspective view of a vanity case or similar article in closed position, showing my new design.

Fig. 2 is a perspective view in open position of one side of the vanity case shown in Fig. 1; and

Fig. 3 is a perspective view in open position of the other side of said vanity case.

The rectangular compartment shown in Fig. 2 is intended to receive powder and/or a powder puff, and the central holder shown in Fig. 3 is intended to receive a plurality of cleansing pads.

I claim:

The ornamental design for a vanity case or similar article, as shown and described.

GEORGE GAMBLE.
